UNITED STATES PATENT OFFICE.

HUBERT F. KRANTZ, OF BROOKLYN, NEW YORK, ASSIGNEE TO KRANTZ MANUFACTURING COMPANY INC., OF BROOKLYN, NEW YORK, A CORPORATION OF NEW YORK.

NO-VOLTAGE RELEASE-SWITCH.

1,399,496.

Specification of Letters Patent.

Patented Dec. 6, 1921.

Application filed December 26, 1917. Serial No. 208,798.

To all whom it may concern:

Be it known that I, HUBERT F. KRANTZ, residing at Brooklyn, in the county of Kings and State of New York, have invented certain new and useful Improvements in a No-Voltage Release-Switch, of which the following is a specification.

This invention relates to a no-voltage release switch.

10 The object of the invention is to provide means whereby a single phase operation on a three phase circuit, and the consequent likelihood of injury to motors or other apparatus connected in the circuit, is rendered impossible.

15 A further object is to provide means whereby flow of current in a three-wire system will be automatically discontinued in case either one of the three protecting fuses 20 is blown.

25 A more particular object is to provide means whereby the flow of current will be automatically discontinued coincident with the blowing of the neutral protecting fuse.

30 A further and more detailed object is to provide a controlling switch common to each of the three fuses, and to provide means associated with the fuses for causing "off" movement of said switch whenever either of 35 the fuses is blown or otherwise disconnected.

Other objects and aims of the invention, more or less specific than those referred to above, will be in part obvious and in part pointed out in the course of the following 40 description of the elements, combinations, arrangements of parts and applications of principles, constituting the invention; and the scope of protection contemplated will be indicated in the appended claims.

45 In the accompanying drawings which are to be taken as a part of this specification, and in which I have shown merely a preferred form of embodiment of the invention:—

Figure 1 is a vertical sectional view through a switch box having its parts constructed and arranged in accordance with this invention.

Fig. 2 is a horizontal sectional view taken substantially upon the plane of line II of Fig. 1.

Fig. 3 is a front elevational view of the parts shown in Figs. 1 and 2, with the cover of the box removed, and

50 Figs. 4 and 5 are diagrammatic views

illustrating different positions of the switch mechanism.

Referring to the drawings for describing in detail the structure which is illustrated therein, the reference character L indicates a box or casing within which all of the current-carrying and movable parts are located, said box preferably having a hinged cover 1 forming its front wall. Within the casing is arranged a partition or barrier 2 of insulating material, said barrier being arranged substantially parallel with the front and back walls of the casing and dividing the interior of the casing into a rear or switch compartment 3, and a front or fuse compartment 4.

Within the switch compartment 3 is arranged an insulated supporting plate 5 carrying the three main line contacts 6, 7 and 8, upon its forward face. Three branch line contacts, 9, 10 and 11 are carried at the rear face of the barrier 2 in positions diagonally opposite the contacts 6, 7 and 8 respectively, and a switch mechanism, as 12, is mounted intermediate said two sets of contacts adapted to control connection therebetween at will.

The switch mechanism 12 includes a carrier 13 that is pivotally mounted by its opposite ends, as 14 and 15, and which carries three insulated double-ended switch blades 16, 17 and 18. Turning of the carrier into "on" position places the blade 16 into engagement with the contacts 6 and 9, the blade 17 into engagement with the contacts 7 and 10, and the blade 18 into engagement with the contacts 8 and 11. A spring 19 is arranged for urging the carrier at all times into "off" position.

A toggle, comprising the links 20 and 21, is arranged for swinging the carrier against the tendency of the spring 19. When the toggle is "broken" then the carrier stands in "off" position, as shown in Fig. 4, whereas when the toggle is "made" the carrier stands in "on" position, as shown in Fig. 5.

The toggle link 20 is constructed in the form of a bell-crank lever of which the link 20 constitutes one arm. The other arm is provided with a pin 22 which is engaged by a link 23, said link in turn being pivotally connected, as at 24 to an operating handle 25. The operating handle 25 is pivotally mounted, as at 26, and projects forwardly through the front wall of the casing.

to a position of accessibility exteriorly of the casing where it preferably carries a handle grip 27 by means of which it may be swung to operate the toggle.

- 5 The link 23 is provided with a longitudinally extending slot 28 for engaging the pin 22 so as thus to provide for unobstructed snap movement of the toggle into its "broken" position when the lower end wall, 10 as 29, is moved upwardly against the pin a sufficient distance to cause the links of the toggle to pass center.

15 A stop 30 is provided for limiting movement of the toggle links in one direction so as thus to retain the toggle "made."

20 An extension arm 31 is also provided upon the toggle link 20 and this arm projects into the path of movement of the end 32 of a control lever 33 which is pivotally mounted 25 upon the forward face of the barrier 2, as at 34.

25 The reference characters G and H indicate two solenoid coils arranged side by side at the forward face of the barrier 2, within the fuse compartment. The cores, as 35 and 36 respectively, of these coils project downwardly from the coils and carry weights, as 37 and 38 respectively, which stand above the lever 33. Each weight preferably has 30 an extension piece 39 which straddles the lever 33 and which provides an arcuate surface 40 arranged to engage the upper edge of the lever whenever the weight descends.

35 The contacts 9, 10 and 11 are electrically connected through the barrier 2 with fuse clips 41, 42 and 43 respectively which are arranged at the forward face of the barrier within the fuse compartment. Mating fuse clips 44, 45 and 46 are provided adjacent the 40 clips 41, 42 and 43 for retaining the fuses 47, 48 and 49, in a well understood manner.

45 Main line wires as 50 extend into the free end of the casing and into engagement with the contacts 6, 7 and 8, while branch line wires as 51 extend outwardly to the load (not shown) from the casing from the fuse clips 44, 45 and 46.

50 When the switch is "on" current, at one instant, may be assumed to feed from the contacts 6 and 8 to the contacts 9 and 11, the fuse clips 41 and 43 through the fuses 47 and 49, fuse clips 44 and 46 and outwardly through the branch line wires. At that same instant the current may be assumed to return through the fuse clip 45, the fuse 48, the fuse clip 42, the contact 10 and the switch blade 17 to the main line contact 7. Shunt circuits extend from the fuse clip 44 along wire 52, through coil G, 55 wire 53, wire 54 to fuse clip 45. Also from fuse clip 46, along wire 55 though coil H and wire 54 to the fuse clip 45.

55 So long as the switch stands in the "off" position, as in Fig. 4, then the arm 31 of the toggle stands free of the lever 33 but

when the operating handle 25 is operated to move the switch "on," as in Fig. 5, then the arm 31 moves downwardly from a position shown in full lines in Fig. 2 to a position shown by the dotted lines in Fig. 2. Co-incident with the downward movement of the operating handle of course current is caused to flow through both of the coils G and H, thus lifting the weights 37 and 38 so that the lever 33 is free to move upwardly into the position shown by dotted lines in Fig. 3. This then is the normal operating position of the mechanism.

60 If now the fuse 47, for instance, should become destroyed, the circuit through said fuse and through the coil G will of course also be destroyed and the coil G will become deenergized and allow the weight 37 to fall upon the lever 33. This will move the lever into its full line position, and will 65 force the arm 31 upwardly a sufficient distance to "break" the toggle, thus allowing the spring 19 to snap the switch "off." On the other hand, if the fuse 49 be destroyed the coil H will become "dead" and the weight 38 will fall upon the arm 31 with the same result. Again, if the fuse 48 be destroyed, although a circuit through both of the coils will be maintained, by reason of the connecting wire 53, yet the current passing 70 will be insufficient to hold the weight 38 elevated, this due to the fact that the weight 38 is made of such increased size and weight relatively to the weight 37, as to be too great to be supported by the divided current. The 75 weight 38, therefore, will fall and throw the switch "off" in the same manner as described with reference to the other fuses.

80 As many changes could be made in this construction without departing from the 85 scope of the invention as defined in the following claims, it is intended that all matter contained in the above description or shown in the accompanying drawings, shall be interpreted as illustrative only and not in a 90 limiting sense.

85 What I claim is:—

1. The combination with a three-pole switch, and means for opening the switch, of two trip coils connected across the respective poles of the switch, and two movable core members therefor having different weights, the core members being of such weights that they engage the said means to open the switch when no current traverses 115 the trip coils and when the trip coils are connected in series across the two poles of the switch.

120 2. Switch mechanism comprising a three-pole switch, a pair of electro-magnets so 125 connected across the poles of the switch that they operate in series on current flowing from one pole to another and in parallel on current flowing from the third pole to the respective first-mentioned poles, a trip bar 130

for moving the switch to open position, and a movable core for each electro-magnet having different weights adapted to engage the bar and move the switch to open position
5 when the energization of the electro-magnets is insufficient to sustain them out of operative relation with the bar.

3. The combination with a three-pole switch having a pivoted operating member,
10 of a pair of core members of different weights for engaging the operating member at different distances from the pivot therefor, the heavier member being disposed nearer to the pivot than the lighter member,
15 and a tripping coil for each core member

for retaining the members out of engagement with the operating member when the coils are energized and so connected across the pole of the switch that interruption of current through either pole of the switch will 20 cause sufficient reduction of current through one coil to permit the core member thereof to drop into actuating engagement with the operating member.

In testimony whereof I affix my signature 25 in the presence of two witnesses.
